(57) **CLAIM**

The ornamental design for a pull tab of slider for slide fastener, as shown and described.

DESCRIPTION

FIG. 1 is a perspective view of the front, bottom and right side of a pull tab of slider for slide fastener showing our new design;

FIG. 2 is front view thereof, the rear view being identical thereto;

FIG. 3 is a right side view thereof, the left side view being identical thereto;

FIG. 4 is a top plan view thereof;

FIG. 5 is a bottom view thereof; and,

FIG. 6 is a front elevational view thereof, the broken line showing of the pull tab in position of use is not part of the claimed design.
